[57] CLAIM

The ornamental design for roof walk for model railway car, as shown and described.

DESCRIPTION

FIG. 1 is the left part of a right side elevational view of a roof walk for model railway car showing my new design, the broken lines are for illustrative purposes only and form no part of the claimed design;

FIG. 2 is the right part of the right side elevational view thereof, the broken lines are for illustrative purposes only and form no part of the claimed design;

FIG. 3 is the left part of a left side elevational view thereof;

FIG. 4 is the right part of a left side elevational view thereof;

FIG. 5 is a front elevational view thereof;

FIG. 6 is a rear elevational view thereof;

FIG. 7 is the right part of a top plan view thereof;

FIG. 8 is the left part of a top plan view thereof;

FIG. 9 is the right part of a bottom plan view thereof;

FIG. 10 is the left part of a bottom plan view thereof;

FIG. 11 is the left part of a perspective view thereof;

FIG. 12 is the center part of a perspective view thereof; and,

FIG. 13 is a right part of a perspective view thereof.
